UNITED STATES PATENT OFFICE

132,430

DESIGN FOR A SPRING CLIP

Solomon Rosenberg, Los Angeles, Calif.

Application October 14, 1941, Serial No. 103,757

Term of patent 14 years

To all whom it may concern:

Be it known that I, Solomon Rosenberg, a citizen of the United States of America, residing at Los Angeles, in the county of Los Angeles, and State of California, have invented a new, original, and ornamental Design for Spring Clips, of which the following is a specification, reference being had to the accompanying drawing, forming part thereof.

Fig. 1 is a front elevational view of a spring clip, showing my new design.

Fig. 2 is an end elevational view of the clip.

Both front and rear sides of the clip are substantially identical in form and appearance.

I claim:

The ornamental design for a spring clip, as shown and described.

SOLOMON ROSENBERG.
